UNITED STATES PATENT OFFICE.

MARTIN D. KUHLKE, OF AKRON, OHIO.

DESIGN FOR A VEHICLE WHEEL-TIRE.

46,283.

Specification for Design.

Patented Aug. 18, 1914.

Application filed June 1, 1914. Serial No. 842,314. Term of patent 7 years.

To all whom it may concern:

Be it known that I, MARTIN D. KUHLKE, a citizen of the United States, residing at Akron, in the county of Summit and State of Ohio, have invented a new, original, and ornamental Design for Vehicle Wheel-Tires, of which the following is a specification, reference being had to the accompanying drawing, forming part thereof.

The figure presented is a view in side ele-

vation of a portion of a vehicle wheel tire, showing my new design.

I claim:

The ornamental design for a vehicle wheel tire, substantially as shown.

MARTIN D. KUHLKE.
